UNITED STATES PATENT OFFICE.

FREDERICK G. GRUEN, OF CINCINNATI, OHIO, ASSIGNOR TO THE D. GRUEN SONS & COMPANY, OF CINCINNATI, OHIO, A CORPORATION OF OHIO.

DESIGN FOR A CLASP FOR BANDS AND STRAPS.

52,649.

Specification for Design.

Patented Nov. 12, 1918.

Application filed January 26, 1918. Serial No. 214,027. Term of patent 14 years.

To all whom it may concern:

Be it known that I, FREDERICK G. GRUEN, a citizen of the United States of America, and resident of Cincinnati, in the county of Hamilton and State of Ohio, have invented a new, original, and ornamental Design for Clasps for Bands and Straps, of which the following is a specification.

Figure 1 is a plan view of a clasp embodying my invention.

Fig. 2 is a side elevation thereof.

The petals of the flowers constitute the female members of the clasp and the centers

of the flowers constitute the male members thereof.

I claim:

The ornamental design for a clasp for bands and straps as shown and described.

In testimony whereof, I have hereunto subscribed my name this 22nd day of January, 1918.

FRED'K G. GRUEN.
